(57) **CLAIM**

The ornamental design for an electronic device with contoured channels, as shown and described.

DESCRIPTION

FIG. 1 is a perspective view of an electronic device with contoured channels according to our new design;

FIG. 2 is an enlarged Perspective view of a portion thereof as indicated in FIG. 1;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof; and,

FIG. 9 an enlarged cross-sectional view thereof taken along line-9-9 in FIG. 7.

The broken lines of the figures depict environment only and form no part of the claimed design.
